CLAIM

The ornamental design for a cardiac catheterization command console, as shown and described.

DESCRIPTION

FIG. 1 is a perspective view of a cardiac catheterization command console showing our new design;

FIG. 2 is a top plan view of our design;

FIG. 3 is a right side elevation of the design; the left side elevation is substantially a mirror image of the right side elevation;

FIG. 4 is a front elevation of our new design;

FIG. 5 is a rear elevation of our design; and

FIG. 6 is a bottom plan view of the design.
